IRONING BOARD

Chester A. Rich and Jesse W. Richardson, Cincinnati, Ohio; said Richardson assignee to said Rich

Application June 26, 1933, Serial No. 677,633

13 Claims. (Cl. 68—10)

This application is concerned with an improvement upon the ironing board disclosed in co-pending application, Serial No. 630,561, filed August 26th, 1932, by Jesse W. Richardson, one of the co-inventors herein.

An object of the instant invention is to augment the force utilized for retaining the board in extended or operative position whereby to attain greater rigidity and stability than has heretofore been attained in devices of similar character.

Another object is to obtain this indicated greater stability and rigidity without impairing the co-operation and functioning of those parts of the device that attain automatic extension and collapse of the various parts by means of a single hand shiftable part thereof.

These and other objects are attained by the means described herein and disclosed in the accompanying drawings, in which:

Fig. 1 is a perspective view of the improved ironing board.

Fig. 2 is a bottom view of the device in a collapsed position.

Fig. 3 is a perspective view of one of the pair of leg spreaders forming a part of the invention.

Fig. 4 is a side view of part 49.

The board or table member 10 has a reduced forward or front end 11. At the rear end 12 thereof is provided, on the under surface thereof, a metal bracket 13 having turned or angularly disposed lugs 14 and 15 at its ends. The bracket or mounting piece 13 is attached to the board in any suitable manner, for example, by means of rivets. To each of the lugs such as 14 and 15 there is pivotally attached rear legs 16 and 17. The inner face of each of the legs is tapered or beveled as indicated at 18 so that when the legs are extended away from the board to positions that the legs normally assume in an operative position of the device, the lower extremities 19 and 20 of the legs may be spaced apart at a greater distance than the distance between the lugs 14 and 15. The legs 16 and 17 will be referred to herein as rear legs. A forward or front leg is provided. The forward or front leg, also referred to as a third leg may comprise a single leg member as shown in the said co-pending application Serial No. 630,561, or it may comprise a pair of shaft members 21 and 22 that may be joined at their lower or free ends by a suitable rivet whereby the shafts 21 and 22 function as does the single leg 25 of the said co-pending application, Serial No. 630,561. To all purposes and intents the members 21 and 22 co-operate and function as a single third leg for the device.

Each of the members 21 and 22 is pivotally mounted at its upper end to the under face 24 of the board 10 by means of suitable brackets 25 and 26. The upper ends of the members 21 and 22 are cut at such an angle as indicated at 27, that when the members 21 and 22 are moved to extended position, the face 27 may have substantial abutment or contact on the under face 24 of the board. The contact of said angle ends 27 of the members 21 and 22 upon the under face 24 of the board 10 substantially limits the extent to which the joined or lower ends 23 of the members 21 and 22 may move toward the rear end legs 16 and 17. While there is some slight flexibility or resiliency in the members 21 and 22, it is to be understood that substantially the indicated limitation of movement is controlled by the said contact of the ends 27 upon the under face of the board 10. The lower or free ends 23 of the third leg structure 21—22 have pivotally attached to them the forward end of a substantially V-shaped connecting rod comprising arms 28 and 29. The apex or base part 30 of the said connecting rod is retained in transverse notches 31 formed in the upper faces of the members 21 and 22 and a suitable washer extends over the notches 31 and thereby confines the said base 30 of the connecting rod to the indicated notches 31. A suitable bolt 32 extends through and between the members 21 and 22 for holding the indicated washer in position. Any other suitable means may be employed for pivotally retaining the base portion of the connecting rod in a determinable position at the lower end 23 of the members 21—22. At the rear ends of the rods 28 and 29 suitable abutment means 33 are provided on each of the arms 28 and 29. The rear ends of the rods 28 and 29 extend slidably through elongated openings 34 provided in the lower ends of cross braces 35 and 36. The abutment means 33 are adapted to engage the lower extremities of cross braces 35 and 36 when the device is fully extended or in operative position. The upper ends of the cross braces 35 and 36 are pivotally connected to the rear legs 16 and 17. The lower portions of the cross braces 35 and 36 are pivotally connected to struts 37 and 38. The rear ends of the struts 37 and 38 are pivotally mounted upon the legs 16 and 17. The struts 37 and 38 form part of a toggle structure. The front ends of the struts 37 and 38 are connected by a transverse or base portion 39 of a U-shaped bar 40 comprising arms or links 41 and 42. The bar 40 is preferably annular in 55

cross section and constitutes part of the toggle structure. The free ends of the arms 41 and 42 are turned outwardly as indicated at 43 and 44, respectively, and the outturned ends 43 and 44 are received in pockets 45 and 46, respectively, provided between U-shaped brackets 47 and 48, respectively, and the under face of the board 10, and to which the brackets are secured. The pockets are elongated in the direction of the length of the board 10, thereby permitting some longitudinal movement of the connection member 40 relative to the board 10. Each of the arms 41 and 42 of the member 40 is provided with an offset or abutment 49. The abutments are produced by turning or bending the member 40 so that substantially a Z-shaped structure is given to each of the arms 41 and 42. The base portion 39 of the member 40 is pivotally mounted upon the struts 37 and 38 and a suitable hand piece 50, mounted upon the base portion 39 of the member 40 intermediate the forward ends of the struts 37 and 38, retains the forward ends of the struts 37 and 38 in opposed relationship. The means for mounting the base portion 39 of the member 40 upon the struts may be similar to that employed for pivotally attaching the apex 39 of the rods 28 and 29 upon the forward and lower end of the third leg structure 21—22. A second U-shaped member 51 has eyes 52 formed at the ends of its arms 53 and 54 and the arms 41 and 42 are slidably received in the eyes 52 of the member 51. The base portion 55 of the member 51 is pivotally mounted upon the lower face of the board 10 by suitable brackets 56. The eyes 52 are adapted to engage the abutments 49 at and shortly before the time that the toggle device comprising struts 37 and 38 and U-shaped member 40 attain the positions that they assume in the fully extended or operative position of the device. The brackets 56 are so positioned relative to the brackets 41 and 48 and the members 40 and 51 are so proportioned that during the movement of the members 40 and 51 through a few degrees of their respective arcs of movement immediately preceding movement of the parts to fully extended position, the member 40 is projected rearwardly along the under surface 24 of the board, thereby placing the struts 37 and 38, legs 16 and 17, connecting rods 28 and 29, and the third leg structure 21—22, under tension for retaining all the parts in a very substantial and rigid relationship. The upper or forward ends of the struts 37 and 38 are so shaped that in the extended position of the device those faces or ends 57 of the struts rest upon and support the under face 24 of the board. The relationship of the toggle structure, third leg structure, rear legs, and cross braces is such that a snap action of the toggle is attained over the dead center of the three pivotal factors A, B and C whenever the hand piece is manipulated for setting up or collapsing the device. At or about the time the three factors A, B, C are aligned when setting up the board, the eyes 52 on the member 51 come into contact with the abutments 49 of the member 40, and the continued movement of the hand piece 50 toward the position that said hand piece assumes in Fig. 1, causes the U-shaped connecting member 40 to be moved rearwardly of the board so that the outturned ends 43 and 44 of the member 40 are moved rearwardly of the point C, wherefore in the set-up position, the forward outwardly extending ends 43 and 44 of the connecting member 40 are disposed intermediate the ends of the

pockets 45 and 46. In collapsing the device, the opposite action of parts takes place.

Attention is directed to the fact that the cross braces 35 and 36 have an angularly disposed bracket member 58 that is pivotally mounted at 59 upon a strut intermediate the pivotal connections A and B of the strut members upon the rear legs and connecting member 40, respectively.

The cross braces 35 and 36 are mounted in such positions upon the legs and struts that they co-operate with the toggle structure in separating the free ends 16 and 20 of the legs when the device is set up into operative position and for bringing the said free ends of the legs together so they will be disposed within the body lines of the board when the device is collapsed.

The toggle structure is so related to the third leg structure 21—22 and the connecting rods 28—29, that the resilient characteristics incident to the third leg structure 21—22, the mounting thereof upon the under face of the board 10, and the connection therewith of the rods 28 and 29, will attain sufficient tension of the various parts that a very firm support for the table 10 is provided. It is obvious that the connections and mountings of the third leg structure upon and with the board and with the struts and rear legs by means of the rods 28 and 29, limit the extent to which the legs 16 and 17 may move rearwardly about the pivotal mountings of said legs upon the lugs 14. It is obvious that the toggle structure is essentially a tensioning device, rather than a means for limiting the rearward movement of the legs 16 and 17. While in a sense the toggle structure does limit the degree to which the legs 16 and 17 may move rearwardly, the said toggle structure is so related to the other parts of the device that the toggle connection is not adapted to remain in a position wherein the points A, B and C are aligned, wherefore except at the moment when the said three points are aligned, the toggle structure does not limit or define the extent of rearward movement of the legs 16 and 17. By so relieving the toggle structure of any limiting action upon the position of the rear legs, it is possible to attain full benefit of the struts 37 and 38 as reinforcing or brace members for the forward or front end of the board. Any tendency of the rear legs to move backward or rearwardly is met and resisted by the co-action of the third leg structure, the top or board 10, and the connections 28 and 29, with the cross braces 35 and 36.

The U-shaped connecting members 40 and 51 constitute a form of compound linkage that projects the struts 37 and 38 toward the rear legs in opposition to the collapsing strain tendency set up by the parts 21, 22, 27, 28 and 29, incident to setting up of the device.

What is claimed is:

1. In a folding ironing table, a board, a pair of legs mounted on said board for swinging together and apart and toward and from the board, a pair of braces pivotally mounted at one of their ends intermediate the ends of said legs, a pair of links pivotally mounted intermediate the ends of the braces and on the bottom of said board so that the legs may be moved to substantially the vertical position, or to a position flat against the bottom of said board, means for projecting the links toward the mountings of the legs on the board as the legs are moved to said first mentioned position, and a pair of cross braces pivotally mounted at one of their ends upon said legs and at their other ends upon said first braces at points inter- 75

mediate the pivot points of the first braces with the legs and with said links.

2. In a folding ironing table, a board, a pair of legs mounted on said board for swinging together and apart and toward and from the board, a pair of braces pivotally mounted at one of their ends intermediate the ends of said legs, a pair of links pivotally mounted intermediate the ends of the braces and on the bottom of said board so that the legs may be moved to substantially the vertical position, or to a position flat against the bottom of said board, means for projecting the links toward the mountings of the legs on the board as the legs are moved to said first mentioned position, a pair of cross braces pivotally mounted at one of their ends upon said legs and at their other ends upon said first braces at points intermediate the pivot points of the first braces with the legs and with said links, a third leg pivotally mounted at one of its ends on the bottom of the board and movable to a position wherein the free end of said leg extends angularly away from the board and from said first pair of legs and the pivotally mounted end thereof engages the bottom of the board, or a position flat against the bottom of the board, and connection means pivotally mounted on the free end of the third leg and having sliding connection with the cross braces adjacent the mounting of the cross braces on the first mentioned braces, said connection means including abutment means for limiting the extent to which the third leg may be moved relative to the pair of legs and first mentioned braces, whereby to place the various table supporting members under tension when the device is in operative position.

3. The combination of a table top, a leg pivotally mounted on the table and so related to the table that the leg may be moved to a substantially vertical position or to a position flat against the bottom of the top, means for limiting movement of the leg beyond said substantially vertical position, a toggle comprising a strut and a link, the strut and link having pivotal connection and each having a second pivotal mounting, said second pivotal mountings being one on the leg and the other on the top, the last referred to pivotal mounting being shiftable along the top toward and from the pivotal mounting of the leg on the top, and a means for projecting said shiftable pivotal mounting toward the pivotal mounting of the leg on the top, incident to movement of the leg to vertical position.

4. In a folding table the combination of a top, a leg pivotally mounted on the top for movement to a position wherein the leg extends substantially vertically or a position flat against the bottom of the top, a strut pivotally mounted upon the leg intermediate the ends thereof, a link pivotally mounted upon the strut intermediate the ends thereof and having a shiftable pivotal mounting upon the top, the pivotal mountings of the strut upon the leg, the link upon the table and the link upon the strut being so related that they are brought into alignment incident to movement of the leg to vertical position, the link and the strut being so related that the pivotal connection therebetween will be positioned on opposite sides of the pivotal mounting of the link upon the board in the folded and set-up positions of the table, said pivotal connection of the link and the strut passing beyond the dead center line between the pivotal mountings of the link and the strut upon the table and leg respectively, incident to folding and setting up of the table, means for

placing tension upon the leg, strut and link assembly as the pivotal mounting of the strut and the link approaches the dead center position between the connection of the link and the strut with the table and leg respectively, and means for moving the link toward the pivotal mounting of the leg on the table as the pivotal mounting of the link and the strut move toward and beyond the said dead center line incident to setting up of the table.

5. A folding table comprising a top board, rear legs pivoted to said board for pivotal movements toward and from the board, a toggle acting brace comprising a pair of struts pivotally connected to said legs and an approximately U-shaped member pivotally connected to the board, the transverse portion of which extends between and is pivotally connected to the forward extended spaced ends of said struts providing a hand grip piece between said struts, said legs and U-shaped member being pivotally connected to the board at such points and the strut elements being of such length that when the legs are turned down from the board the toggle acting brace will be buckled by said U-shaped member against the bottom of the board, and a second U-shaped member pivotally mounted between the pivotal mountings of the first U-shaped member and the legs upon the table and having sliding and abutting connection with the first mentioned U-shaped member whereby to project the first mentioned U-shaped member toward the legs as the legs are turned down from the board.

6. A folding table comprising a top board, rear legs pivoted to said board for pivotal movements toward and from the board, a pair of elongated pockets provided upon the under surface of the board, a toggle acting brace comprising a pair of struts pivotally connected to said legs and an approximately U-shaped member having outwardly extending projections formed at the ends of the arms thereof and positioned in said elongated pockets, the transverse or base portion of the U-shaped member extending between and being pivotally connected to the forward extended spaced ends of said struts, said legs, pockets and U-shaped member being so connected to the board and at such points, and the strut elements being of such length that when the legs are turned down from the board, the toggle-acting brace will be buckled by said U-shaped member against the bottom of the board, and means pivotally mounted on the board between the pockets and the pivotal mountings of the legs upon the board and having sliding and abutting connection with the U-shaped member for projecting the U-shaped member toward the pivotal mountings of the legs on the board and for moving the out turned ends upon the U-shaped member in the elongated pockets incident to turning down of the legs.

7. A folding table comprising a top board, rear legs pivoted to said board for pivotal movement toward and from the board, a pair of elongated pockets provided upon the under surface of the board, a toggle-acting brace comprising a pair of struts pivotally connected to said legs and an approximately U-shaped member having outwardly extending projections formed at the ends of the arms thereof and positioned in said elongated pockets, the transverse or base portion of the U-shaped member extending between and being pivotally connected to the forward extended spaced ends of said struts, said legs, pockets and U-shaped member being so connected to the board and at such points, and the strut elements being

of such length that when the legs are turned down from the board, the toggle-acting brace will be buckled by said U-shaped member against the bottom of the board, means pivotally mounted on the board between the pockets and the pivotal mountings of the legs upon the board and having sliding and abutting connection with the U-shaped member for projecting the U-shaped member toward the pivotal mountings of the legs on the board and for moving the out turned ends upon the U-shaped member in the elongated pockets incident to turning down of the legs, and means for placing the toggle-acting brace under tension as the connection between the U-shaped member and the strut approaches the dead center line between the mountings of the U-shaped member and the struts upon the top board and legs, respectively.

8. A folding table comprising a top board, rear legs pivoted to said board for pivotal movement toward and from the board, a pair of elongated pockets provided upon the under surface of the board, a toggle-acting brace comprising a pair of struts pivotally connected to said legs and an approximately U-shaped member having outwardly extending projections formed at the ends of the arms thereof and positioned in said elongated pockets, the transverse or base portion of the U-shaped member extending between and being pivotally connected to the forward extended spaced ends of said struts, said legs, pockets and U-shaped member being so connected to the board and at such points, and the strut elements being of such length that when the legs are turned down from the board, the toggle-acting brace will be buckled by said U-shaped member against the bottom of the board, means pivotally mounted on the board between the pockets and the pivotal mountings of the legs upon the board and having sliding and abutting connection with the U-shaped member for projecting the U-shaped member toward the pivotal mountings of the legs on the board and for moving the out turned ends upon the U-shaped member in the elongated pockets incident to turning down of the legs, a third leg structure having pivotal mounting upon the board intermediate the mountings of the rear legs and the pockets and movable to a position flat against the bottom of the board or to a position wherein the free end thereof projects away from the board and from the rear legs and wherein the pivotally connected end of said third leg structure abuts the under surface of the board, cross braces extending between the rear legs, and the upper end of each thereof having a pivotal mounting on one of the legs and a second pivotal mounting upon one of the struts intermediate the ends thereof and adjacent the pivotal mountings of the struts upon the rear legs, the lower ends of each of the braces being angularly turned and each having an elongated slot extending on opposite sides of the apex of the angle effected by turning the lower ends of the braces and a substantially V-shaped connecting rod having its apex pivotally positioned upon the free end of the third leg structure adjacent the free end thereof, one each of the arms of the V-shaped member extending through an elongated slot in one of the cross braces and having an abutment at the end thereof adapted to engage the cross braces when the rear legs are turned down from the board and when the table is set up in operative position, the third leg structure, V-shaped member, cross braces and the connections thereof with various parts of the assembly placing tension upon the toggle-acting

brace as the pivotal connection between the U-shaped member and the struts approaches the dead center line of the toggle-acting brace.

9. In a folding ironing table the combination with a board member, legs associated therewith for movement to extended position for supporting the board member and to folded position relative to the table and means for so connecting the legs to the table and to one another that movement of the legs to table supporting positions places said means and the legs under a condition of stress, said means including a toggle structure comprising members pivotally connected together between certain of the legs and the board member so that the members may be moved on opposite sides of a dead center line which includes said pivotal connections, and means for advancing the toggle members bodily toward the legs after said toggle members have passed over dead center line incident to setting up of the table.

10. The combination of a table, legs for supporting the table and pivotally connected to the table for movement to extended and folded positions, means connecting the legs whereby force applied to one leg is transmitted to another leg when the table is set up with said legs in extended positions, means limiting the movement of the legs beyond extended positions of the legs and cooperating with the connecting means in attaining a condition of tension in the leg connecting means when the legs are extended, means for moving at least one of the legs to extended position whereby to subject another of the cooperating legs to an initial force and auxiliary means for augmenting the initial force by increasing the pressure with which the legs are pressed in opposition to the means for limiting the movement of the legs beyond extended position.

11. The combination with a folding table comprising a board or table member, a leg pivoted for movement relative to the board member to extended or folded positions, means under strain incident to extension of the leg tending to move the leg toward its folded position, a strut pivoted on the leg and compound linkage being of such length and connected to the strut and to the table at such places that in extending the leg, the strut and part of said linkage assume a straight line relation between the connection of the strut to the leg and the connection of said part of the linkage to the table and another part of said linkage being adapted to project the strut toward the leg and in opposition to the tendency of the leg to move toward its folded position.

12. The combination with a table comprising a top, legs hingedly connected at an end of each to the top, a toggle comprising two portions hinged together at the approximate ends of each, said two portions connecting the legs and the table and adapted to have their hinged together parts moved back and forth over the dead center line passing through the connections of the toggle portions together and to the legs and the table, and means including supplemental support means, for placing the legs under stress whereby to buckle the toggle members against the top when the legs are turned down from the board, of means pivoted relative to the top at a location rearwardly of the connection between the top and that toggle portion which is connected to the top, for moving the toggle toward the legs as the hinged together parts thereof pass beyond said dead center line incident to turning down the legs from the table and for

maintaining approximately the same stress upon the legs that the legs are subjected to at the time the toggle portions are in dead center alignment.

- 5 13. The combination with a table comprising a top, a leg hingedly connected at its one end to the top, a toggle comprising two portions hinged together at the approximate ends of each, said two portions connecting the leg and the table
10 and adapted to have their hinged together parts moved back and forth over the dead center line passing through the connections of the toggle portion together and to the leg and the table,

and means including supplemental support means, for placing the leg under stress whereby to buckle the toggle members against the top when the leg is turned down from the board, of means for moving the toggle toward the leg as the hinged together parts of the toggle pass beyond said dead center line incident to turning down the leg from the table and for maintaining approximately the same stress upon the leg that the leg is subjected to at the time the toggle portions are in dead center alignment. 10
